CONTAINER

William Tamoschat, New York, N. Y., assignor
to David H. Zell, Brooklyn, N. Y.

Application June 7, 1941, Serial No. 396,990

1 Claim. (Cl. 220—60)

This invention relates to containers, such as compacts, vanity or cigarette cases and has for its general object and purpose to simplify and reduce the cost of manufacture of such articles by the provision of means for securely retaining the cover of the case in closed position without employing separate latching or locking elements attached to the case body or cover.

It is a more particular object of the invention to provide a case or container in which a sheet metal case body has an upstanding resiliently yieldable marginal wall and the hinged cover has a relatively narrow and rigid marginal rim or flange provided with an outwardly projecting lip adapted to coact with said body wall and locally distort the same from normal position whereby said wall is caused to frictionally coact with said lip and retain the cover in closed position.

With the above and other objects in view, the invention consists in the improved container, and in the form, construction and relative arrangement of its several parts as will hereinafter be more fully described, illustrated in the accompanying drawing and subsequently incorporated in the subjoined claim.

In the drawing wherein I have shown one simple and practical embodiment of the invention and in which similar reference characters designate corresponding parts throughout the several views:

Fig. 1 is a front side elevation of the container with a cover thereof in open position.

Fig. 2 is a diametrical sectional view, the cover being closed, and,

Fig. 3 is an enlarged fragmentary detail vertical section showing the coacting relationship between the cover latching lip and the body wall of the container.

For purposes of illustration, I have selected a case or container of circular form, though it will be evident that the present invention is applicable as well to such containers of rectangular or other shapes or forms. The container body, generally indicated at 5, is formed of pressed or stamped sheet metal and includes the bottom wall 6, formed at its outer edge with a continuous inwardly opening bead 7 and the upstanding marginal wall 8. This marginal wall is of such depth that it is capable of local resilient distortion from its normal position at substantially right angles to the plane of the bottom wall 6.

The lid or cover for the case body, generally indicated at 9, also is formed from stamped or pressed sheet metal and is hingedly connected to the marginal wall 8 of the case body at one

side of the latter in any well-known manner, as indicated at 10.

The cover section of the container includes the top wall 11 also formed at its outer edge with a continuous inwardly opening bead 12 and a relatively narrow rim or flange 13 extending inwardly therefrom. This flange is comparatively rigid and at a point diametrically opposite to the hinge 10 is formed with the outwardly pressed concavo-convex lip 14. It will be understood that the cover flange 13 is of such dimensions relative to the body wall 8 that when said cover is in closed position, the cover flange 13 has snug fitting contact against the inner face of said body wall.

As indicated in Figs. 2 and 3 of the drawing, when the container is used as a compact or a vanity case, the body section 5 of the container which receives the cosmetic materials and powder puff or the like, is provided with a liner of paper or other suitable material, indicated at 15, which covers the upper surface of the bottom wall 6 and has its outer edge engaged in the hollow bead 7. Similarly, a mirror 16 may be applied to the inner surface of the cover wall 11 with its outer edge portion engaged in the hollow bead 12 of said cover.

In the use of the device, it will be understood that when the cover member 9 is moved from the open position shown in Fig. 1 to the closed position of Fig. 2, the outwardly projecting rigid lip 14 on the cover flange 13 will first contact the edge of the upstanding body wall 8 and, upon the application of pressure, at this point said body wall will be sprung outwardly or distorted from its normal position as clearly shown in Fig. 3 of the drawing. Thus the lower edge of the lip 14 moves downwardly against the inner face of the body wall against increasing frictional resistance as said wall is outwardly sprung from its normal position. Therefore, when the cover member is fully closed, it will be evident that the inward bearing frictional pressure of the body wall 8 against the outer surface of the lip 14, as indicated at 17, will be sufficiently great to securely hold or retain the cover in closed position against accidental outward opening movement relative to the container body and, in order to open said cover member, it is necessary to apply considerable manual lifting force against the edge bead 12 of the cover member.

From the foregoing description considered in connection with the accompanying drawing, it will be seen that I have provided a case or container with cover holding or latching means hav-

ing self-contained coacting latch parts and which eliminates the employment of additional or separate latching elements secured to the body and cover sections of the container. Thus an appreciable saving in time and labor in the manufacture of such containers is realized and the cost thereof to the consumer correspondingly reduced. I have herein referred to a structural embodiment of the device, which in practical use has been found entirely satisfactory for the purpose in view. Nevertheless, it is manifest that, with respect to the mechanical details of the present disclosure, my invention is susceptible to incorporation in other structural forms. Therefore, it is to be understood that the privilege is reserved of resorting to all such legitimate changes or modifications in the form, construction and relative arrangement of the several cooperating parts as may fairly be considered as within the spirit and scope of the appended claim.

I claim:

A container comprising hingedly connected body and cover sections of sheet metal, said body section having a resiliently yieldable marginal wall whose upper free edge is defined by the thickness of the metal sheet and said cover section having a relatively narrow, comparatively rigid, marginal rim adapted to fit snugly within said body wall when the cover sections is closed, said cover rim having a non-yieldable, outwardly projecting, concavo-convex lip, said lip projecting beyond the circumference of the marginal rim of the cover and having an end edge terminating in the plane of the free edge of said rim and adapted to engage the edge of said body wall and, under pressure, locally displace the same outwardly from its normal position and frictionally coact with the inner face thereof to retain said cover section in its fully closed position.
